UNITED STATES PATENT OFFICE.

HARTWICH D. TODT, OF SAN FRANCISCO, CALIFORNIA.

DEHYDRATING APPARATUS.

Application filed March 17, 1923. Serial No. 625,753.

To all whom it may concern:

Be it known that I, HARTWICH D. TODT, a citizen of the Republic of Germany, residing at San Francisco, in the county of San Francisco and State of California, have invented new and useful Improvements in Dehydrating Apparatus, of which the following is a specification.

This invention relates to improvements in dehydrating apparatus.

The principal object of this invention is to provide a tunnel drier or dehydrater having simple and efficient means for maintaining and retaining a uniform heat and air circulation.

Another object is to provide means whereby the partly moistened air is re-heated and used over again.

A further object is to provide the air circulation without employing mechanical means such as fans or blowers for causing the circulation.

Other objects and advantages will be apparent during the course of the following description.

In the accompanying drawings forming a part of this specification, and in which like numerals are employed to designate like parts throughout the same,

Figure 1 is a vertical longitudinal section of my device,

Figure 2 is a cross section taken on the line 2—2 of Figure 1, looking in the direction of the arrow, and

Figure 3 is a perspective view of one of the drier trays.

Applicant is aware of the fact that tunnel driers have been employed for the purpose of dehydrating vegetables and the like.

These devices, in order to obtain a proper circulation, employed the use of fans or blowers which are expensive and run at a substantially uniform speed, with the result that it is difficult to control the amount of circulation.

In the accompanying drawings wherein for the purpose of illustration is shown a preferred embodiment of my invention, the numerals 5, 6, 7, 8 and 9 refer to vertical uprights, which support a roof 11.

A suitable siding 12 is secured to the uprights, while the lower portions of the ends are closed as shown at 13 and 14. Secured to the uprights 5 to 9 are angle iron supports as shown at 16.

It will be noted by viewing Figure 1 that

these supports slant from one end toward the other, the loading end being higher than the unloading end. In order to simplify the drawings, I have shown but one set of trays supported upon the top supports. These trays, four in number, are designated by the numerals 17, 18, 19 and 21.

A series of pivoted doors 22 serve to close the loading end, while a series of pivoted doors 23 serve to close the unloading end. These doors are closed by gravity as will be noted by viewing Figure 1. The structure thus far described merely forms a drying chamber within which a plurality of trays are positioned.

The numeral 24 designates baffle plates and it will be noted that these baffle plates are positioned adjacent the unloading end and are of varying sizes from the top toward the bottom. These baffle plates are secured to the underside of the supports 16.

At 26 is shown a deflector plate having one end in close proximity to the lowermost baffle 24 and having its opposite end inclined downwardly as best shown in Figure 1.

At 27 I have shown a fire box within which a fire of any type may be placed, which fire box is suitably insulated and has an air space 28 formed thereabove. A shield 29 partially encloses a port to this air space 28.

Air which is heated while passing over this fire box will enter the drying chamber as indicated by the arrows.

A series of fire tubes 31 extend from the fire box 27 to a smoke chamber 32. This smoke chamber opens outwardly through an opening 33 and to a stack 34, it of course being understood that there is a similar stack provided on each side of the drying chamber as best noted in Figure 2.

Disposed within this stack 34 is a conduit 36. This conduit communicates with the interior of the drying chamber through a slotted port 37. A ventilating pipe 38 is connected to a flue 39 which flue in turn connects with the conduit 36. The stack 34 is in turn connected to a similar flue 41 overlying the flue 39 and has a pipe 42 secured thereto.

A division plate 43 rests upon the roof 11 at a point within the ventilating pipe 38 and serves to prevent eddy currents forming in the stack.

A chamber 44 is formed at a point below

the smoke chamber 32 and has communication with the interior of the drying chamber. At 46 I have shown a plurality of pipes of large diameter which pipes communicate with the chamber 44 and extend to a point beneath the grate bars 47 of the fire box. A passageway 48 is also provided from the chamber 44 to the space surrounding the pipes 46 and 31.

10 The circulation of the air within my device is as follows:—

Assuming that a fire has been built in the fire box 27, the smoke therefrom will pass through the tubes 31 to the smoke chamber 32 where it will divide and pass through the openings 33 into the stacks 34, passing upwardly through the flue 41 and out of the pipe 42. At the same time the heat given off by the fire and the smoke will cause a 20 thermo circulation which will draw air through the feed pipes 49 which air will enter the space around the pipes 31 and as the same becomes heated it will rise as indicated by the arrows, striking the deflector 25 plate and travelling toward the discharge end of the drying chamber. At the same time air will enter beneath the shield 29 passing over the top of the heated fire box to the space 28 and will also join the previously described heated air. This air will now pass upwardly and a portion will be diverted between each tier of trays as the same comes into contact with the baffle plates 24. This heated air will travel the 30 length of the chamber and some will be exhausted through the slotted port 37, into the conduit 36 and will then pass upwardly 35 and out of the pipe 38.

Some of the moisture-laden air will, however, drop and will return as indicated by the arrow to the chamber 44 where some of it will pass through the passageway 48 and again enter the normal circulation. Some 40 of this air, however, will enter the pipes 46 and will be conducted to a point beneath the grates of the firebox.

It is of course understood that all of the parts are suitably insulated so as to prevent 45 undue radiation of the heat employed for the drying.

It is to be understood that the form of

my invention herewith shown and described is to be taken as a preferred example of the same, and that various changes in the shape, size and arrangement of parts may 55 be resorted to without departing from the spirit of the invention or the scope of the subjoined claims.

Having thus described my invention, I claim:—

1. In a device of the character described, a drying chamber having a plurality of supports, parallel spaced on the sides thereof, and adapted to receive trays slidably disposed thereon, a plurality of baffle plates 65 of varying lengths secured to said supports, a deflector plate mounted below said supports and inclined downwardly from the lowermost of said baffle plates and means for conducting heated air upwardly against said 70 deflector plate, means for exhausting a portion of said heated air from said chamber, and means for re-heating the balance of said air, substantially as and for the purpose 75 specified.

2. In a device of the character described, a drying chamber having a plurality of supports secured thereto, said supports being adapted to receive trays slidably positioned thereon, a plurality of hinged doors adapted 80 to give access to said drying chamber, said doors being disposed at opposite ends thereof, a plurality of baffle plates positioned adjacent one end of said chamber, said plates being of varying width, a deflector plate 85 positioned beneath said supports, a firebox located beneath said chamber, a plurality of fire tubes extending from said firebox to a point adjacent the opposite end of said chamber from said firebox, a smoke chamber 90 adapted to receive the gases of combustion from said firebox, a stack communicating therewith, means for conducting fresh air to a point beneath said fire tubes, a chamber located beneath said drying chamber, and 95 means for conducting a portion of the air from said chamber to a point beneath said firebox, substantially as and for the purpose specified.

In testimony whereof I affix my signature.

HARTWICH D. TODT.
